DETERMINATION OF DENSITIES OF FLUIDS IN WELLS

Filed July 16, 1938

Fig. 1

UNITED STATES PATENT OFFICE

2,235,064

DETERMINATION OF DENSITIES OF FLUIDS
IN WELLSRaymond T. Cloud, Tulsa, Okla., assignor to
Stanolind Oil and Gas Company, Tulsa, Okla.,
a corporation of Delaware

Application July 16, 1938, Serial No. 219,617

7 Claims. (Cl. 265—44)

This invention relates to means for the determination of the specific gravities, densities or relative densities of well fluids and more particularly of the fluids present in oil wells.

5 It is an object of my invention to provide apparatus which will permit the measurement of the densities of well fluids at varying depths within a well. Another object of my invention is to provide apparatus of this type which can be operated quickly and conveniently and which will give readings at or above the surface of the ground. A further object is to provide apparatus for logging a well by the determination of the densities of the fluids within it. A still further object of my invention is to provide a device 10 for the determination of the point of gas, oil or water intrusion into a well. Additional objects, advantages and uses of my invention will become apparent as the description thereof proceeds.

15 20 The device of my invention includes an element responsive to the density of the well fluid surrounding it and means for indicating and/or recording this density. Preferably this indication or recording is made at the surface of the well.

Such a device has many important uses in connection with oil well practice. Thus for instance, one method of using such a device is in the logging of bore holes. This can be done by 25 circulating a drilling mud, preferably one having a high specific gravity, within the well and then lowering the head of the liquid in the well, for instance by pumping or bailing out a portion of the drilling mud. This reduction in hydrostatic 30 head permits the fluids contained in the formations penetrated by the well to enter the bore hole. By the use of my device the specific gravity of the column of liquid can then be measured at various depths or continuously as the device is 35 raised and lowered. Where the measured specific gravity is that of the circulated mud, it is obvious that no fluid has entered the well but when the specific gravity is found to have been lowered it is indicated that fluids from the strata 40 opposite such points have entered. If the specific gravity has been lowered but does not fall below unity or below the gravity of oil-field brines it is apparent that water or brine has entered at this point but where the gravity has fallen to less than unity, it is apparent that oil has entered or in 45 some instances that gas has entered and become emulsified with the drilling mud.

Further, a device of this type is useful in that it permits the rapid and accurate location of the water-oil interface within an oil well and this is 50

an advantage in bottom hole sampling work. The device can also be used to determine the densities of fluids in the bottoms of so-called distillate wells and to locate accurately the fluid levels in such wells. It can likewise be used in 5 running tests within a well to determine the effect of changes in pressure, etc. on fluids, particularly fluids of the distillate type, present within a bore hole.

The invention will now be described in more 10 detail in connection with the accompanying drawing which forms a part of this specification and is to be read in conjunction therewith. In the drawing:

Figure 1 is a diagrammatic elevation of a portion of a bore hole and the equipment above it, illustrating in highly simplified form one embodiment of my invention;

Figure 2 is a sectional elevation of a preferred embodiment of that portion of my apparatus 20 which is used within the well;

Figure 3 is a sectional elevation taken along the line 3—3 of Figure 2;

Figure 4 is another sectional elevation taken along the line 4—4 of Figure 2; and 25

Figure 5 is a highly simplified diagrammatic elevation showing the underground portion of a modified form of apparatus in accordance with my invention.

Turning to Figure 1, it will be seen that a bore 30 hole 11 penetrates beneath the surface of the earth 12 and that the device is lowered into this bore hole to measure the specific gravities or densities of the fluids within it. Essentially this device consists of a weight 13 acting on a spring 35 14. The strain occasioned by the weight is, of course, proportional to its effective or apparent weight in the particular fluid in which it is immersed. The result is that varying fluid specific 40 gravities vary the point of contact between contactor 15 and resistance 16.

Insulated electrical conductors and supporting cables 17, 18 and 19 are raised and lowered together by means of hoist 20. While these are shown as three separate lines they will in practice 45 usually be a single supporting cable containing three insulated conductors.

From hoist 20 the electrical circuits pass through slip rings (not shown) to conductors 21, 22 and 23 which are extensions of conductors 17, 50 18 and 19 respectively. A source of voltage 24 is connected across conductors 22 and 23. Conductors 21, 22 and 23 lead to a resistance ratio type of telemetering device 25. This device contains two coils 26 and 27 mounted on a common 55

shaft at right angles to each other. These coils are placed in a magnetic field provided by magnet 28.

It will be apparent from the circuits shown 5 that the currents flowing through the two coils will vary in accordance with the position of contactor 15 on resistance 16 since the circuit which includes coil 26 contains that portion of resistance 16 which is below contactor 15 while the 10 circuit which includes coil 27 contains that portion of resistance 16 which is above contactor 15. The difference in current flow through these two coils tends to cause them to rotate in the magnetic field provided by magnet 28 and this rotation 15 is opposed by spring 29 which is anchored at post 30. The amount of rotation is a function of the specific gravity of the fluid in which weight 13 is immersed and this degree of rotation is shown on scale 31. It will be apparent that 20 this scale can be calibrated in arbitrary terms, in specific gravity, in pounds per gallon or in any other desired unit.

It will also be apparent that other types of tele-metering devices are well known and can be used 25 and that my invention is by no means limited to the use of the resistance ratio type of device.

As an illustration of the variation in apparent 30 weight to be expected from a device of this type we may consider the case of an aluminum block having a volume of 100 cubic inches lowered into a well which contains mud weighing 11 pounds per gallon. The weight of the block in this instance is 9.7 pounds in air while the apparent 35 weight in the mud, water and oil (specific gravity .65) is as follows:

Apparent weight, pounds		
Circulating mud	4.94	
Water	6.1	
Oil	7.4	

The underground portion of one form of my device is shown in Figures 2, 3 and 4. In Figure 2 it will be seen that a case 32 which can suitably be made from some insulating material of the 45 synthetic plastic type is divided into two compartments 33 and 34 by means of partition 35. Means for access to these compartments are, of course, provided but are not shown in these views. Compartment 33 is open to the well fluids through 50 holes 36 and 37 while compartment 34 is filled with a relatively non-compressible insulating liquid such as transformer oil and is kept out of contact with the well fluid by means of gland 38 which will be described in detail hereinafter. 55 Weight 13 is supported from arm 39 which is rigidly mounted on shaft 40 carried between bearings 41 in such manner as to give a minimum resistance to rotation. This rotation is opposed by coil spring 14 anchored to post 42.

60 The shaft also carries a contactor arm 15 (best seen in Figure 3) which makes contact with resistance 16. From the two ends of this resistance insulated conductors 18 and 19 lead out of compartment 34 through double headed binding posts 43 and 44 and thence into 3-conductor cable 45 which supports case 32 and its contents through U-bolt 46 and passes at its upper end to hoist 20. Similarly, a third insulated conductor 17 leads from a point in metallic contact with 65 contact arm 15 through double headed binding post 47 to 3-conductor cable 45. It is of course understood that the outside portions of these double headed binding posts must be insulated from contact with well fluids.

70 75 Gland 38, to which reference has previously

been made, serves the purpose of keeping well fluids out of compartment 34 and at the same time makes it possible to maintain the same pressure in compartment 34 as in compartment 33, thus preventing fracture of the case 32 or 5 partition 35 due to varying well pressures as the device is raised or lowered. Ring 48 is attached to shaft 40 and to it is claimed a flexible oil-resistant tube 49. This clamping is done by ring 50 which is equipped with flanges 51 which are 10 pulled together by means of bolt 52 as can be seen in Figure 4. The other end of this flexible tube is clamped by means of ring 53 to a projection 54 on partition 35. Flexible tube 49 can be made of a synthetic oil-resistant rubber composition such as Duprene or Thiokol. It is of 15 such length and sufficiently thin as to offer very little resistance to the rotation of shaft 40 within the limits required and is also sufficiently flexible to permit equalization of the pressures in compartments 33 and 34. 20

It will be apparent from this description of one embodiment of my invention that the specific 25 gravity of the fluid within the well at the level of the specific gravity-responsive device will control the force operating on weight 13 and thus give an indication or record of the specific gravity of the well fluid. However, it is not essential to rely on 30 measurements of weight forces in order to determine the specific gravities of liquids encountered in the well since the density of the liquid column is a function of the pressure differentials encountered in traversing this column. Thus

$$\frac{dp}{dz} = \rho$$

Where

p = pressure
 z = depth
 ρ = density

40 or the rate of change of pressure with depth is proportional to the density of the liquids at the point where the readings are taken, so that if two pressure devices separated by a small distance are lowered into the well arranged so as to record the differential pressure between the two devices included between the two pressure devices, will be proportional to the readings obtained. 45

A device of this type is shown in Figure 5 50 which is confined to the sub-surface portion of the equipment. A telemetering device and other above-surface equipment identical with that shown in Figure 1 can be used. The device of Figure 5 includes two compartments 55, each 55 of which has a diaphragm 56. The forces exerted on these diaphragms are, of course, proportional to the pressures of the well fluids on the outside of them. These forces tend to rotate contactor arms 57 and thus vary the positions of these contactors on resistances 58. Conductors 17, 18 and 19 corresponding exactly to the conductors of the same numerals in Figure 1 lead to the above-surface equipment and specific gravity can thus be measured by the device of Figure 5 just as in 60 the case of the device of Figure 1. 65

While I have described my invention in connection with certain preferred embodiments thereof, it is to be understood that these are by way of illustration and not by way of limitation 70 and I do not mean to be limited thereby but only to the scope of the appended claims.

In the claims, where "density" measurement is referred to, I mean to include also the measurement of specific gravity, relative density, etc. and 75

where I speak of "indicating" values of this type I also mean to include the recording of such values.

I claim:

5. 1. A device for determining well fluid density which comprises a weight suspended in said well fluid, a spring opposing the force exerted by gravity on said weight, means responsive to the position of said weight under the influence of 10 gravity, means for raising and lowering the foregoing elements within a well and means associated with said responsive means for forming an indication corresponding to the position of said weight.
15. 2. A device for determining well fluid density which comprises a weight suspended in said well fluid, a spring opposing the force exerted by gravity on said weight, means responsive to the position of said weight under the influence of 20 gravity, means for raising and lowering the foregoing elements within a well and telemetering means to produce above the surface of the ground an indication corresponding to the density of the fluid in which said weight is immersed.
25. 3. A device for determining well fluid density which comprises a weight constructed and arranged to be inserted in a well, means constructed and arranged to be inserted in said well and to suspend said weight in the fluid present in said 30 well, a spring associated with said weight and said means and constructed and arranged to be inserted in said well for opposing the force exerted by gravity on said weight, a contact arm responsive to the position of said weight, a resistance contacted by said contact arm, means for maintaining said resistance and the contact arm in contact therewith out of contact with said well fluid to prevent short circuiting of said resistance, and means associated with said resistance and 35 said contact arm for forming an indication corresponding to the position of said weight.
4. A device for determining well fluid density which comprises a weight constructed and arranged to be inserted in a well, means constructed 45 and arranged to be inserted in said well and to suspend said weight in the fluid present in said well, a spring associated with said weight and said means and constructed and arranged to be inserted in said well for opposing the force exerted 50 by gravity on said weight, a contact arm constructed and arranged to be inserted in said well responsive to the position of said weight, a resistance constructed and arranged to be inserted in said well contacted by said contact arm, means 55 for maintaining said resistance and the contact arm in contact therewith out of contact with said well fluid to prevent short circuiting of said re-
- sistance, telemetering means associated with said resistance and said contact arm for forming above the surface of the ground an indication corresponding to the position of said weight and means for raising and lowering said weight, said contact 5 arm and said resistance in said well.
5. A device for determining the densities of well fluids comprising means responsive to the pressure of well fluids at one level, means responsive to the pressure of well fluids at a second 10 level, means for producing electrical variations in accordance with the differential response of said two responsive means and a telemetering device associated with said last-mentioned means for indicating above the surface of the well the density of the fluid in which said two responsive means are immersed.
6. Apparatus for logging a well comprising density-responsive means adapted to be inserted in a well, means for lowering said density-responsive 20 means into said well, means associated with said density-responsive means and adapted to be inserted in a well for producing electrical variations in accordance with the varying response of said density-responsive means, means for transmitting 25 said electrical variations to the top of said well, and means associated with the last-mentioned means and located above the surface for indicating the relative densities at various depths of the fluids in said well in which said density-responsive 30 means is immersed.
7. A device for determining well fluid density which comprises two compartments, one of said compartments being open to the penetration of well fluids and the other being closed to the penetration of well fluids, a substantially fluid tight seal between said two compartments, a density-responsive member disposed in the first of said compartments, means yieldingly opposing the movement of said density-responsive member, 35 force transmission means associated with said density-responsive member and passing through said seal, a contact arm associated with said force transmission means disposed within the second of said two compartments and responsive to the 40 position of said density-responsive means, a resistance contacted by said contact arm disposed within the second of said two compartments, all of the previously mentioned elements being constructed and arranged to be inserted in a well, 50 means for raising and lowering said elements within said well, and telemetering means associated with said resistance and said contact arm for forming above the surface of the ground an indication corresponding to the position of said 55 density-responsive means.

RAYMOND T. CLOUD.
